RIVETER OR THE LIKE HAVING A PRESSURE MULTIPLYING DEVICE

Raoul Nissim, London, England, assignor to Resistance Welders Limited, Inverness, Scotland

Application August 20, 1947, Serial No. 769,571
In Great Britain October 5, 1943Section 1, Public Law 690, August 8, 1946
Patent expires October 5, 1963

1 Claim. (Cl. 60—54.5)

1

The present invention relates to a fluid-operated device for multiplying pressure, and may be used to operate any form of tool requiring the use of a high pressure, such as a riveting tool operating either by squeezing a solid rivet or by pulling an oversize mandrel through a hollow rivet.

The operation of such devices off a compressed air supply is already common practice, and as the pressure (80 to 100 lbs. per square inch) at which compressed air is usually supplied is too low to operate the devices directly off the air supply line, some form of pressure multiplier is interposed between the air supply and the tool to give a pressure of perhaps 6000 lbs. per square inch. Thus, for example, it is known to use air pressure to move the differential piston of a hydraulic piston and cylinder of comparatively large diameter and stroke; the air pressure applied to the larger face of the differential piston being transferred to liquid on the smaller face with a multiplication factor equal to the ratio of the areas of the two faces. The pressure developed in the liquid in this manner is then transferred, via a flexible pipe, to the tool effecting the riveting or other operation.

A differential piston and cylinder used in this way constitutes a form of pressure multiplier, but although multiplication adequate for most purposes can be achieved in this manner, the tool suffers from certain disadvantages. Thus, in order to give the required pressure multiplication and the required work, the differential piston must be of comparatively large cross-section and have a fairly large travel; consequently owing to its weight and bulk, it cannot be incorporated in the hand tool, but must be mounted separately and connected to the tool by a flexible pipe capable of withstanding the fully multiplied pressure. Another disadvantage arises out of the fact that in the operation of squeeze riveters, for example, the squeezing members have to be moved apart, for convenience of handling, a distance greater than that required for the actual riveting. In the known apparatus described the fully multiplied pressure is used to move the squeeze members apart and/or bring them together up to the riveting position, whereas both of these movements could be performed with the employment of far less power.

It is an object of the present invention to provide a tool which is easy and cheap to manufacture, is of small bulk and weight, is easily and flexibly handled, which does not require the use of very high pressure hose between the multiplier and the tool, and in which the fully

multiplied power is used only for the actual riveting or other operation.

In order that the nature of the invention may be more clearly appreciated a preferred example will now be described with reference to the accompanying diagrammatic drawing of a riveting tool in which the figure illustrates a simple tool in which the whole of the multiplication of pressure required for the power stroke is achieved in the tool itself.

Referring to the drawing, a pressure-applying tool comprises a casing 9 to which is attached a pipe 10 through which, from a supply reservoir 11, compressed air at a comparatively low pressure is supplied to a chamber 12. Pressure of the fluid causes downward movement of a differential piston 13 against the resistance of a spring 14 thereby compressing a fluid, such as oil, contained in a chamber 15. A second piston 16 is held from downward movement by a spring 17 until pressure in the chamber 15 has attained a predetermined level sufficient to overcome the action of the spring.

As the differential piston 13 moves downwardly the fluid contained in the chamber 15 is forced through a port 18 into a passage 19 in a stem 20 of the piston 16 and thence into a chamber 21. The pressure of the fluid acts on a piston 22 of a ram 23 to make what will be called the approach stroke of the ram. It will be noted that this approach stroke is made with fluid at a comparatively low pressure which is not multiplied, but as this pressure acts on the large face of the differential piston 13 to displace the oil and therefore the smaller piston 22, the ram 23 moves a greater distance than the piston 13. A return spring 24 is slightly compressed during the approach stroke.

When the approach stroke has been completed and the ram 23 bears against the work which is not shown but is located between the ram 23 and an anvil 25 the differential piston 13 is still acted upon by the compressed air entering by the pipe 10 and the fluid pressure in the chamber 15 will therefore increase until the predetermined level is reached when the piston 16 is displaced against the action of spring 17, air in chamber 26 escaping through ports 27.

When a valve 28 formed integrally with the piston 13 abuts against a valve seating 29 on the stem 20, port 18 is closed and the members 13 and 20 thereafter move as a single unit and act as a single differential piston giving a multiplication of specific pressure. Continued movement of the differential piston 13 displaces the fluid in the passage 19 and chamber 21 to cause

the power stroke of the ram 23. It will be appreciated that the specific pressure or pressure per unit area, applied to the piston 22 is equal to the specific pressure applied to the piston 13 multiplied by a factor equal to the ratio of the cross-sectional areas of pistons 13 and 22 respectively.

The fluid pressure applied through the pipe 10 may be cut off by valve 11A and the chamber 12 opened to atmosphere, the springs 14, 17, 24 and 30 then causing the several parts and the fluid to return to their initial positions.

The low pressure supply may be that given by compressed air, steam or gas or other compressible fluid whilst the fluid operating against the ram may be incompressible such as water or oil.

I claim:

A pressure applying tool including a first cylinder, a first piston in said cylinder operated by fluid pressure to effect a power stroke, a liquid storage chamber bounded on opposite sides respectively by said piston and by a resiliently loaded movable wall, a second cylinder smaller than the first, a second piston in said second cylinder, a passage in said second piston connecting the storage chamber to the second cylinder, a ram actuated by the pressure of liquid

in said second cylinder, cooperating means on said first piston and said second piston for closing said passage after a predetermined relative movement of said pistons, and resilient means acting on said second piston to resist its movement, whereby fluid pressure acting on the first piston first displaces said piston relative to the second piston to displace liquid from the storage chamber into the second cylinder until the completion of the predetermined relative movement, after which the passage is closed, and the second piston moved mechanically by the first piston to apply pressure to the liquid in the second cylinder.
